(57) **CLAIM**

The ornamental design for a shopping cart as shown and described.

DESCRIPTION

This application is related to and incorporates by reference U.S. patent application Ser. No. 29/857,743 entitled "Shopping Cart" filed on an even date herewith. It is understood that any material in U.S. patent application Ser. No. 29/857,743 that is not present in this application forms no part of the claimed design.

FIG. 1 is a top, rear perspective view of the shopping cart showing our new design;

FIG. 2 is a front view thereof;

FIG. 3 is a rear view thereof;

FIG. 4 is a right side view thereof;

FIG. 5 is a top view thereof;

FIG. 6 is a bottom view thereof; and

FIG. 7 is a left side view.

FIG. 8 is a rear, perspective view of the shopping cart of FIG. 1 with unclaimed portions of the shopping cart, other than a rear gate with child seat, being removed to more clearly show the claimed subject matter of the design;

FIG. 9 is a front view thereof;

FIG. 10 is a rear view thereof;

FIG. 11 is a right side view thereof; and,

FIG. 12 is a top view thereof.

In the drawings, the broken lines show portions of a shopping cart which form no part of the claimed design.
